United States Patent

[19]

Lee

[11] Patent Number: Des. 363,429

[45] Date of Patent: **Oct. 24, 1995

[54] COVER FOR CONTAINERIZED PRINTER'S
INK

5,339,981 8/1994 Kral 220/227

[76] Inventor: William Lee, 221 N. Hutchinson,
Spokane, Wash. 99212

OTHER PUBLICATIONS

[**] Term: 14 Years

Top left image of first page of foreign (assumed British)
Patent No. 26,063, Nov. 1906.

[21] Appl. No.: 19,420

Primary Examiner—Alan P. Douglas
Assistant Examiner—Robert M. Spear
Attorney, Agent, or Firm—Keith S. Bergman

[22] Filed: Mar. 1, 1994

[57] CLAIM

[52] U.S. Cl. D9/454

The ornamental design for cover for containerized printer's
ink, as shown and described.[58] Field of Search ..... D9/434—455, 499;
4/293; 215/231; 220/221—222, 227, 578;
222/386

DESCRIPTION

[56] References Cited

FIG. 1 is a perspective view of my cover for containerized
printer's ink showing my new design in use, the broken lines
partially showing an ink can being for illustrative purposes
only and forming no part of the design;
FIG. 2 is a perspective view of my cover;
FIG. 3 is a top plan view of FIG. 2;
FIG. 4 is a bottom plan view of FIG. 2.
FIG. 5 is a side view of FIG. 2, all other side views being
identical thereto; and,
FIG. 6 is a diametrical cross-sectional view of FIG. 1, all
diametrical cross-sectional views being identical thereto.
